UNITED STATES PATENT OFFICE.

JAMES H. DOWNEY, OF SAN ANTONIO, TEXAS.

BLOWPIPE.

1,182,150.

Specification of Letters Patent.

Patented May 9, 1916.

Application filed February 5, 1916. Serial No. 78,452.

To all whom it may concern:

Be it known that I, JAMES H. DOWNEY, a citizen of the United States, residing at San Antonio, in the county of Bexar and State of Texas, have invented a new and useful Blowpipe, of which the following is a specification.

The present invention appertains to blowpipes or hydrocarbon torches, and aims to provide a novel and improved device of that character.

It is the object of the invention to provide a blow pipe using a Bunsen burner, having assembled therewith in a novel manner an air blast tube extending to the mouth of the burner, whereby when the air blast is not used, a hot Bunsen flame is provided, and when the air blast is used, an extremely hot needle flame is provided.

It is also the object of the invention to provide novel means for supporting the blowpipe, whereby it can be set upon a table, bench, or other support, and whereby the blowpipe can be handled or manipulated by the hand in a convenient and desirable manner.

The invention also aims to reduce the structure to its simplest and most inexpensive form, without depreciating the value and utility thereof.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing wherein:

Figure 1 is a side elevation of the blowpipe and its supporting means, the base being shown in section. Fig. 2 is a longitudinal section of the blowpipe, taken on the line 2-2 of Fig. 1, portions being broken away and others being shown in plan. Fig. 3 is a sectional detail taken on the line 3-3 of Fig. 1.

In carrying out the invention, there is provided a suitable standard 1 which is also used as a handle for the blowpipe, and which is provided at its lower end with a reduced tapered shank 2 to fit tightly in the tapered aperture or socket 3 of an iron or other suit-

able base 4. The upper end of the standard 1 is equipped with a ferrule 5, provided at its end with a longitudinal slot 6 in which is pivoted the contacting terminals 7 of a strap or band 8, the terminals 7 extending radially from the band 8 and being pivoted within the slot 6 by means of a screw 9 engaged through the ferrule 5 and terminals 7. The screw 9 can be tightened for clamping the terminals or ears 7 within the slot 6, and when the screw is loosened, the band 8 can be swung about the screw 9 as an axis, or an axis arranged transversely of the standard or handle 1. The band 8 is provided at one side with an outwardly offset portion or loop 10, through which is engaged a clamping screw 11, whereby the band will be contracted when the screw 11 is tightened.

The blowpipe embodies a Bunsen burner including the tubular barrel or mixing tube 12, which is fitted snugly within the band 8 to be supported by the standard 1, and which has secured within its basal end, a plug 13. The plug 13 has a pair of apertures through which extend in a longitudinal direction, a pair of metallic tubes 14 and 15. The tube 14 is a gas supply tube and the tube 15 is an air blast tube. A diametrical pin or rivet 16 is engaged through the barrel 12 and plug 13 to secure the plug in place. The protruding terminals of the tubes 14 and 15 are curved, as at 17, away from the axis of the barrel 12 for the connection of the hose or flexible conductors connected to the source of gas and air under pressure. The air blast tube 15 extends longitudinally within the barrel 12, and is offset, as at 18, between the ends of the barrel 12, whereby the portion of the tube 15 between the offset 18 and the tip 19 is arranged axially or concentrically of the barrel 12. The tubes 14 and 15 where they pass through the plug 13 are disposed at opposite sides of the axis of the barrel, and the tip 20 of the tube 14 terminates adjacent the closed end of the barrel or the plug 13. The tip 19 of the tube 15 terminates within the mouth of the barrel 12. The barrel 12 is provided adjacent its closed end with a suitable number of air inlet openings or apertures 21, two diametrically opposite ones being illustrated, and the tip 20 of the tube 14 being disposed near said openings, whereby the gas delivered into the barrel 12 will suck in air, in the manner of an ordinary Bunsen burner, whereby the air will admit with the gas to provide a perfect

combustible mixture, which will burn under all conditions with a smokeless flame. Thus, even though the air blast is not used, a smokeless hot flame is provided. By reason 5 of the air entering the openings 21 admixing with the gas, before the gas reaches the tip 19 of the air blast tube 15, a more perfect combustion of the gas will result, resulting in a hotter flame. A Bunsen flame is provided 10 when the air blast is not used, in order that the object to be soldered or otherwise acted upon can be effectively heated, and then when the air blast is turned on, this provides an extremely hot needle flame.

15 The barrel 12 in extending through the band 8 can be clamped thereby, by tightening the screw 11 to contract the band, and when the band is loosened, the barrel 12 can be rotated about its axis, to bring the terminals 17 of the gas and air blast tubes to one side or the other, or to any suitable point, out of the way. Furthermore, when the band 8 is loosened, the barrel 12 can be adjusted longitudinally, whereby the openings 20 21 can be moved partially within or completely out of the band 8. This band 8 will therefore serve as a shutter or valve controlling the flow of air through the openings 21, whereby the supply of air into the Bunsen 25 burner can be regulated as desired. When the standard 1 is supported by the base 4, the blowpipe can be supported upon a table, bench, or other support, and when the screw 9 is loosened, the blowpipe can be swung to various positions in a vertical plane, it being an easy matter to rotate the blowpipe about a vertical axis also. The blowpipe can thus be supported in various angular positions, and by detaching the standard 1 from the

base 4, the standard can be used as a handle 40 for manipulating the blowpipe, and the handle and barrel can be swung to various angles relative to one another as may be found more convenient.

Having thus described the invention, what 45 is claimed as new is:

1. A blowpipe embodying a barrel having an air inlet opening adjacent one end, a plug fitted in said end, and gas and air blast tubes extending through said plug longitudinally 50 of the barrel, the gas tube terminating adjacent said opening, the air blast tube having an offset between the ends of the barrel, the end of the air blast tube terminating at the other end of the barrel and that portion 55 of the air blast tube between the offset and end being arranged axially of the barrel.

2. In a device of the character described, a supporting member, a pivot carried thereby, a band having terminals engaging said 60 pivot, one side of the band having an outstanding loop, a clamping element engaged through said loop, and a blowpipe fitted within said band.

3. In a device of the character described, 65 a base having a tapered socket, a standard having a tapered shank to fit in said socket, the standard being adapted for use as a handle, a band pivoted to the standard, and a blowpipe fitted within the band.

In testimony that I claim the foregoing as my own, I have hereto affixed my signature in the presence of two witnesses.

JAMES H. DOWNE.
